UNITED STATES PATENT OFFICE.

ABRAHAM G. JENNINGS, OF BROOKLYN, NEW YORK.

DESIGN FOR ORNAMENTAL FABRIC.

SPECIFICATION forming part of Design No. 24,522, dated July 30, 1895.

Application filed June 26, 1895. Serial No. 554,139. Term of patent 14 years.

To all whom it may concern:

Be it known that I, ABRAHAM G. JENNINGS, a citizen of the United States, residing at Brooklyn, county of Kings, and State of New York, have invented and produced a new and original Design for Ornamental Fabric, of which the following is a specification.

The leading feature of my design is an ornamental fabric of essentially the ornamentation and representation exhibited in the accompanying drawing, which shows a section of fabric embodying my design.

In the drawing, A is the fabric ornamented as follows: Crossing the fabric are dark irregular bands *a a*, spaced apart and presenting a tufted appearance or effect. Intervening between bands *a a* are contrasting lighter irregular bands *b b*, also presenting a tufted appearance or effect, the general effect of the

tufted appearance of the bands being to produce an apparent encroachment of adjacent bands into each other, as exhibited in the drawing, by the tufted salient angles *c c* of the dark bands *a a*, apparently overhanging and encroaching upon the body of the lighter bands *b b*, producing a partial obscuration thereof, and the tufted salient angles *d d* of the lighter bands *b b* apparently encroaching upon the body of the darker bands *a a*.

What I claim is—

The design for an ornamental fabric substantially as described and shown in the accompanying drawing.

ABRAHAM G. JENNINGS.
